UNITED STATES PATENT OFFICE.

FRANCES IRENE HOFFMAN, OF SEATTLE, WASHINGTON.

LINGERIE CLASP.

Application filed October 2, 1928. Serial No. 309,871.

This invention relates to the class of buckles, buttons and clasps and pertains particularly to a new and novel type of clasp designed especially for use as a lingerie clasp.

5 The primary object of the present invention is to provide a clasp which may be easily and quickly applied to a garment and which may be readily adjusted without having to be detached either from the garment or from a supporting strap thereon.

10 A further object of the invention is to provide a clasp of the character above described, which is of such simple construction that the parts may be readily stamped from metal blanks and assembled with a minimum of trouble.

15 Further objects and advantages of the present invention will become apparent as the description of the same proceeds, and the invention will be best understood from a consideration of the following detailed description taken in connection with the accompanying drawing forming part of this specification, with the understanding that the invention is 20 not confined to any strict conformity with the showing of the drawing, but may be changed or modified so long as such changes or modifications mark no material departure from the salient features of the invention as expressed 25 in the appended claims.

30 In the drawing—

Figure 1 is a view in elevation of a clasp embodying this invention, showing the same applied;

35 Fig. 2 is a side elevational view of the clasp;

Fig. 3 is a longitudinal sectional view of the clasp and attached portions of the garment; and

40 Fig. 4 is a central transverse sectional view of the clasp.

Referring to the drawing in detail, wherein like numerals of reference indicate corresponding parts throughout the several views, the numeral 1 indicates the back plate of the 45 clasp embodying the present invention, which plate is preferably of elongated rectangular design and has each longitudinal edge turned slightly as indicated at 2, the central portion of each turned edge 2 having projecting therefrom the forwardly extending plate 3 from the opposite edges of which plate extends an arm 4. These arms are arranged in spaced relation to the adjacent edges or flanges 2 of the back plate, thus setting up at each end and at 55 each side of the back plate a longitudinally extending slot 5.

Extending transversely of each end of the back plate 1 is a row of teeth 6. Pivotaly mounted at each end of the back plate and upon the ends of the arms 4 is a latch 7, that 60 end of each latch lying adjacent an end of the back plate being provided with an inwardly extending tongue 8 which, when the latch is swung to closed position, or in other words lies against its supporting arms and parallel 65 with the back plate, engages against the adjacent teeth 6 to hold the edge of a garment, such as that indicated at 9, or a ribbon such as that indicated at 10 in position. The sides of the latches 7 are turned to form longitudinally 70 extending flanges 11 which overlie the adjacent arms 4 when the latches are in closed position and these flanges also provide means for securing the latches to their supporting arms, a suitable pin 12 being passed through the 75 arms and the adjacent latch flanges for this purpose.

The adjacent edges of the latches are cut away as indicated at 13 to facilitate manipulations of the latches by the finger, and the 80 back plate 1 is similarly cut away at its central portion to permit the extending of a garment strap therethrough when same is being held by the clasp in the manner shown. When the present clasp is in use for supporting 85 an article of clothing having shoulder straps or ribbons, engagement of the top edge of the garment is effected by swinging out one of the latches and inserting the edge of the garment between the arms supporting 90 this latch and the back plate 1. The latch is then swung to closed position, which operation causes the tongue 8 thereof to press the body of the garment against the adjacent teeth 6. For engaging the garment shoulder 95 strap the other latch is then swung outwardly from the back plate and the end of the strap inserted between the attached end of the latch and the adjacent teeth and passed outwardly through the opening formed in the 100 back plate 1, until the proper adjustment is made, whereupon the latch may be swung to closed position in the same manner that the garment edge is engaged.

From the foregoing description it will be 105 readily seen that the present clasp may be readily placed upon a garment and designed to be quickly adjusted to hold the garment in a comfortable position.

Having thus described my invention, what 110 I claim is—

1. A clasp of the character described, com-

prising a back plate having a plurality of teeth formed across two opposite edges thereof, side plates projecting from the back plate, a pair of latches, means for securing each of said latches at an end of said plate to the side plates, means forming a part of each latch designed to coact with adjacent teeth for the engagement of an article of clothing, and flanges at opposite sides of the latches overlying the side plates when the latches are closed.

2. A clasp of the character described, comprising a back plate, a toothed flange formed across each end thereof, a forwardly extending plate body at the central portion of each of two opposite edges of the back plate, laterally extending arms carried by

each of said last mentioned plates and projecting in spaced parallel relation to the adjacent edge of the back plate forming therewith inwardly extending slots at each side thereof to receive an article of clothing, a latch mounted at each end of the back plate upon said arms, each having a clothing engaging portion extending transversely of the back plate to abut the inner face of a toothed flange, and flanges at opposite sides of the latches designed to overlie said forwardly extending plate bodies when the latches are closed.
